UNITED STATES PATENT OFFICE

WILLIAM H. BENEDICT, OF COSCOB, CONNECTICUT, ASSIGNOR TO CHICAGO PNEUMATIC TOOL COMPANY, OF NEW YORK, N. Y., A CORPORATION OF NEW JERSEY

SPRING HANDLE ATTACHMENT FOR ROCK DRILLS

Application filed July 22, 1927. Serial No. 207,811.

This invention relates to handle attachments adapted for use with rock drills of the cradle or shell mounted type.

Among the objects of the invention are to simplify the construction and to cheapen the cost of manufacture of such attachments, to permit the convenient application of the attachment to a drill of the described type, to confine the wear to extended bearing surfaces engaging the wing portions or projecting flanges of the drill, and in general to improve prior devices in the interest of more efficient and satisfactory service.

In order to illustrate the invention one concrete embodiment thereof is shown in the accompanying drawings in which:

Fig. 1 is a plan view of a drill with the handle attachment applied thereto;

Fig. 2 is a right end elevational view of the parts shown in Fig. 1;

Fig. 3 is a side view showing the drill in elevation save for the feed nut projection which is in section and showing the attachment in section substantially on the line 3—3 of Fig. 1;

Fig. 4 is a fragmentary transverse sectional view substantially on the line 4—4 of Fig. 3; and

Fig. 5 is a detail view showing a slight modification.

In the drawings the attachment is disclosed as applied to a drill A of the cradle or shell mounted type having on its lower side the "wings" or projecting flanges a (Figs. 1, 2 and 4) adapted to engage the slides of the shell mounting and the usual feed nut projection b (Figs. 1, 2 and 3).

The handle attachment includes a block 6 which may be either a casting or a forging. It is of such shape as to span the shell engaging portions of drill A, (see Fig. 4) and has axial recesses 7 slidably receiving wings a of the drill. Block 6 carries a handle 8 secured thereto in any suitable manner as by rods 9 having reduced ends extending through aligned perforated ears 6a, 6b, nuts 10 being utilized to prevent withdrawal of the rods, which may extend beyond nuts 10 as indicated in Fig. 1 for a purpose later to be described. As indicated in Figs. 2 and 3

rods 9 may be bent so as to dispose handle 8 in line with the axis of the drill.

The handle attachment is arranged for limited yielding movement axially of the drill in both directions to protect the operator of the drill from the vibration of the latter when in operation. The feed nut projection b is utilized to fix the midpoint of such permissive movement and to form a fixed abutment for the yielding means. As indicated in Fig. 3, block 6 has its ends at least partly spanned by walls 11 and 12 disposed in the plane of feed nut projection b. Interposed between abutment walls 11 and 12 on the one hand and projection b on the other are provided resilient members such as coil springs 13 and 14. By preference the abutment members at either end of the springs provide guide or centering members for the latter. For this purpose abutment walls 11 and 12 may provide projections 11a and 12a. The centering means in relation to feed nut projection b preferably takes the form of socket or cup members 15 projecting within the bore of the feed nut projection and in these sockets the ends of the springs are seated. This arrangement not only accurately centers the springs but also permits the entire attachment either to be made quite compact or to use long springs 16 or both, since practically the entire bore of feed nut projection b is made available for a useful purpose.

To enable the attachment to be applied to a drill, one abutment wall, such as 12, is made separable from block 6, preferably being part of a cap piece 16 which is clamped to block 6. For the purpose of securing the cap piece in place the extended ends of side rods 9 may be used as indicated in Fig. 1, the rods passing through ears 18a and 18b on cap piece 16 and having washers 19 and nuts 20 applied to their outer ends. Fig. 5 indicates an alternative construction in which cap piece 18' is secured to block 6' by cap screws 21 extending through ears on cap piece 18' and having threaded engagement with aligned ears on block 6'. In this form the rods 9' carrying the handle are shorter and the reduced ends thereof extend

through a single elongate ear on the block 6.

In applying the handle attachment to a shell mounted drill, the latter is first removed from its mounting. Socket members 15 are

5 inserted in the bore of feed nut projection b. Springs 13 and 14 are placed in socket members 15. Block 6 is then disposed as indicated in Fig. 4 with its recesses 7 in alignment with "wings" a on drill A and is slid

10 upon the drill toward feed nut projection b until the free end of spring 13 telescopes over guide projection 11a. Block 6 is forced still further forward to compress spring 13 and cap piece 18 is then placed in engagement

15 with the end of block 6 to confine spring 14 on the opposite side of the feed nut projection, the ends of rods 9 extending through ears 18a and 18b. Washers 19 and nuts 20 are applied. This completes the attaching

20 of the spring handle and the drill is ready for use as a manually supported tool. The handle attachment is quickly removed by reversing the above steps.

25 While the invention has been herein disclosed in what are now considered to be preferred forms, it is to be understood that the invention is not limited to the specific details thereof, but covers all changes, modifications and adaptations within the scope of the appended claims.

I claim as my invention:

1. The combination with a drill of the cradle or shell mounted type of a handle attachment therefor having portions slidably fitting the shell engaging portions of the drill and providing a fixed abutment and a removable abutment disposed on opposite sides of the feed nut projection of the drill, and in line with the axis of the latter, 35 springs interposed between said abutments and the feed nut projection and comprising the sole connection between said attachment and said feed nut projection, and centering means on said feed nut projection for said springs telescopingly supporting the latter within the bore of said projection.

2. The combination with a drill of the cradle or shell mounted type of a handle attachment therefor having portions slidably fitting the shell engaging portions of the drill and providing a fixed abutment and a removable abutment disposed on opposite sides of the feed nut projection of the drill, and in line with the axis of the latter, 50 coil springs interposed between said abutments and the feed nut projection, and comprising the sole connection between said attachment and said feed nut projection, and centering means for said springs on both 55 said abutments and said projection, said projection centering means disposing a portion of one of said springs within the bore of said projection.

3. The combination with a drill of the 65 cradle or shell mounted type of a handle at-

tachment therefor having portions slidably fitting the shell engaging portions of the drill and providing opposing abutments disposed on opposite sides of the feed nut projection of the drill and in line with the axis 70 of the latter, one of said abutments being detachable to permit application and removal of said attachment, coil springs interposed between said abutments and the feed nut projection, socket or cup members at the ends 75 of the feed nut projection extending at least partly within the bore of the same, one end of each of said springs being received by said members to maintain the springs in place.

4. The combination with a drill of the 80 cradle or shell mounted type of a handle attachment therefor comprising a block arranged to span the lower portion of the drill and having recesses slidably receiving the "wings" or projecting flanges of the drill, 85 said block having at its ends transverse abutments disposed in line with the axis of the feed nut projection of the drill, one of said abutments being detachable from said block to permit application and removal of the attachment, socket members in the feed nut projection of the drill, and coil springs engaging said members on the one hand and said abutments on the other to permit limited yielding movement of the handle relative to the drill axially in both directions to relieve 90 the operator of shocks.

5. A spring handle attachment for drills of the cradle or shell mounted type comprising a block having recesses slidably to receive the "wings" or projecting flanges of the drill, 100 said block having a transverse abutment wall integral therewith and arranged to be disposed in line with the axis of the feed nut projection of the drill, a cap member releasably secured to said block providing a second abutment wall opposed to and spaced from said first wall, inwardly directed centering projections on said abutment walls, and coil 105 springs for interposition between said abutment walls and the feed nut projection of the drill and for engagement with said centering projections.

Signed by me at New York city, New York this 13th day of July, 1927.

WILLIAM H. BENEDICT.
